Atty:

UNITED STATES PATENT OFFICE.

BENJAMIN LAWRENCE, OF NEW YORK, N. Y., ASSIGNOR TO LOUISA LAWRENCE, OF SAME PLACE.

PEN-HOLDER.

SPECIFICATION forming part of Letters Patent No. 365,827, dated July 5, 1887.

Application filed January 17, 1887. Serial No. 224,573. (No model.)

To all whom it may concern:

Be it known that I, BENJAMIN LAWRENCE, a citizen of the United States, and a resident of New York city, in the county of New York and State of New York, have invented certain new and useful Improvements in Pen-Holders and Means for Making the Same, of which the following is a specification.

My invention relates to that class of pen-holders comprising an outer barrel or sleeve and an inner barrel or nib-piece. Heretofore these parts have been secured together in various ways, but particularly by riveting, which, however, is an objectionable mode of fastening, on account of its slowness and costliness, and for other reasons known to those skilled in the art. Another well-known way of securing the two barrels together is by cutting out and depressing a transverse loop in the outer one, and a longitudinal tongue in the inner one, and passing the tongue through the loop; but to this construction the objection exists that it is expensive and imperfect, the parts being liable to pull asunder during the extraction of a pen.

My invention has for its main objects to fasten the sleeve and nib-piece together neatly, expeditiously, cheaply, and securely; and to these ends it consists in a novel construction of pen-holder, and in a means for making pen-holders, as will be hereináfter more fully described, and particularly pointed out in the appended claims.

In the accompanying drawings, Figure 1 is an elevation of a pen-holder embodying my invention. Fig. 2 is a cross-section of the same, taken at the line $x-x$, and drawn on an enlarged scale. Fig. 3 is an enlarged perspective view of the nib-piece or inner barrel. Fig. 4 is a like view of the sleeve or outer barrel. Fig. 5 is a vertical longitudinal section, enlarged, taken at the line $y-y$ of Fig. 1. Fig. 6 represents a press used in carrying out my invention. Fig. 7 is a perspective view of the male and female dies used for cutting out and depressing the tongues of the pen-holders. Fig. 8 is an enlarged cross-sectional view of the dies and the inner and outer barrels, and illustrating the operation of cutting out and bending down the tongues.

In the several views the same parts will be found designated by the same numerals and letters of reference.

A represents the handle of the pen holder; B, the outer barrel or sleeve, and C, the inner barrel or nib-piece. The sleeve and the nib-piece are both made of metal and are provided with transverse tongues lettered, respectively, *b* and *c*. When fitted together, the tongue *c* of the nib piece lies below the surrounding metal from which it was cut, and the tongue *b* of the sleeve enters the opening in the nib-piece formed by the cutting out and bending inward of the tongue *c*.

By having the tongues *b* and *c* cut transversely of the barrels and bending them inward so that the outer tongue engages with the transverse opening in the nib-piece formed by the cutting out of its tongue, the barrels are held securely together against longitudinal movement, the side edges of the tongue *b* lying between and against the side edges or walls of the opening in the nib-piece and resisting any tendency to push or pull the barrels apart. In practice, I cut out and depress these transverse tongues at a single operation.

For that purpose I use an ordinary stamping or punching press provided with suitable dies. At Fig. 5 is represented such a press, in the head D of which is fitted a sliding block, E, carrying at its lower end a male die or punch, F. To the bed-plate G of the press is secured a plate, H, having an upright portion, I, which is perforated to admit the threaded shank of the cylindrical horizontally-arranged female die J, and the latter is held firmly in place by a clamping-nut, K, as shown.

The female die is formed with a transverse depression or opening in its periphery, three of its edges being adapted to co-operate with corresponding edges of the punch and assist in cutting out the tongues. The front edge, 1, of the opening at which the points of the tongues are cut and the side edges, 2 and 3, stand higher than the rear flat portion or surface, 4, on which the roots of the tongues are supported during the cutting-out and bending operation. At Fig. 5 the female die is perforated to permit the escape of dirt, grit, &c., and at 5' a gage and steadyng-pin is provided.

The male die or punch is formed with a cutting-edge at .6 for the points of the tongues, and with side cutting-edges, 7, for the sides of the tongues.

5 The press is provided with a foot lever or treadle, L, connecting-rod M, and a lever or arm, N, for reciprocating the punch holder or block E.

Having sufficiently explained the means 10 employed by me in carrying on the manufacture of my improved pen-holders, I will now describe the manner in which said means are used in fastening together the sleeve and the nib-piece.

15 The nib-piece is inserted within the sleeve to about the extent illustrated at Figs. 1 and 5, and the two are then slipped upon the female die until the crotch 8 of the nib-piece comes to a stop against the pin 5. Through 20 the action of the foot-lever L and its connections the punch F is then brought down forcibly and made to cut out at a single stroke the two coincident transverse tongues *b* *c* and bend them both downwardly (or inwardly) until the tongue *c* enters the depression in the 25 female die and the tongue *b* enters the opening in the nib-piece left by the cutting out and depression of the tongue *c*, all as clearly shown.

30 The female die or mandrel preferably fits loosely within the nib-piece, and after the cutting out and bending down of the tongues the barrels may be lifted bodily until the tongue *c* clears the cut-out in the lower die and then 35 pulled off; or, after the cutting out and bending down of the tongues, the barrels may be turned together slightly in the direction of the arrow at Fig. 8 until the tongues ride on the unbroken surface of the mandrel and then 40 be slipped off.

Although I have shown the point of the transverse tongue *b* depressed to exactly fill the opening left by the depression of the tongue *c*, it will be understood that it may be

bent down farther if desired, the only requisite being that it shall interlock itself with the transverse opening in the nib-piece, so as to preclude a pulling out or pushing in of the latter during the insertion or extraction of a pen. 45

Having now so fully described my improved construction of pen-holder and my novel means for making the same that any one skilled in the art may understand them, what I claim as new, and desire to secure by Letters 55 Patent, is—

1. A pen-holder consisting of the nib-piece having a transversely-depressed tongue, and the sleeve having a coincident transverse depressed tongue entering the opening in the 60 nib-piece left by the depression of its tongue, whereby the said nib-piece is held against longitudinal movement, as set forth.

2. The combination of a cylindrical female die having a depression with cutting-edges 65 and serving as a support for the nib-piece and sleeve, a male die also provided with cutting-edges, and means for bringing the two dies together and causing the simultaneous cutting out and bending down of coincident tongues 70 in the nib-piece and sleeve.

3. The combination of a horizontally-arranged cylindrical female die having a depression with cutting-edges and serving as a support for the nib-piece and sleeve, a male 75 die also provided with cutting-edges and arranged vertically over said female die, and means for bringing the two dies together and causing the simultaneous cutting out and bending down of coincident tongues in the 80 nib-piece and sleeve.

Signed at New York city, in the county of New York and State of New York, this 15th day of January, A. D. 1887.

BENJAMIN LAWRENCE.
